DISPLAY DEVICE

Carl M. Sisk and Mildred W. Sisk, Matamoras, Pa.

Application March 26, 1948, Serial No. 17,334

8 Claims. (Cl. 40—126)

1

This invention relates to display devices utilized for advertising purposes, and more particularly to a device of this type which is adapted to display a characteristic container for the product to be advertised, such as a soft drink or other beverage bottle.

One object of our invention is to provide a novel device of the type indicated, which will display a product container, or bottle, in a unique and attention-attracting manner.

Another object is to provide such a device in which various attention-attracting features are combined in such manner as to quickly and effectively convey to an observer a certain quality, condition, or characteristic, of the product, intended to induce the sale thereof.

A further object is to provide such a device having certain structural and functional features of advantage over the similar devices of the prior art.

An additional object is to provide such a device in which a liquid, such as colored or uncolored water, is caused to continuously flow over the outside of the product container, or bottle, in novel manner, so as to enhance the appearance, or effectiveness, of the display device in general, and impart an attention-attracting motion feature to the device.

It is also an object to provide such a device having means arranged to cause periodic variation of the liquid flow directed against the product container, or bottle, thereby creating a novel fluctuating water flow effect around the bottle.

Other objects include the provision of such a device which variously embodies certain features of our invention, for example, a display housing structure having the novel appearance illustrated by the drawings; a support for a product container, such as a beverage bottle provided with a closure cap, which support is arranged adjacent the top of a reservoir containing a liquid, such as water; a liquid circulating system arranged to direct the liquid flow generated by the system, downwardly against the top of the bottle cap, so that the liquid will be spread by the cap in all directions, thereby to form a transparent water curtain about the outside of the bottle; selectively adjustable control means operative to determine the extent of said directed liquid flow; means arranged to effect cyclic operation of said selectively adjustable liquid flow control means; adjustable means for determiningly varying the cyclic operation of said liquid flow control means; a liquid discharge member or nozzle, connected in said liquid cir-

2

culating system in such manner as to permit selective spacing and axial alignment of the nozzle relative to the bottle cap; and means arranged to permit mounting of the device on a building wall, or other upright support.

With these and other objects in view, which will become more apparent from the following detailed description of our improvements illustrated in the accompanying drawings, the invention comprises the novel display device, elements, features of construction and arrangement of parts in cooperative relationship, as more particularly defined by the hereto appended claims.

In the drawings:

15. Figure 1 is a front elevational view of a display device embodying our invention.

Fig. 2 is a rear elevational view of the device shown in Fig. 1, with a certain portion of the frame indicated in dot-and-dash outline and a wiring diagram of the electrical parts included.

20. Fig. 3 is an elevational sectional view of the device, taken substantially as indicated by the arrows 3—3 on Fig. 1.

Fig. 4 is an enlarged elevational detail sectional view, taken substantially as indicated by the arrows 4—4 on Fig. 3.

Fig. 5 is a fragmentary detail plan sectional view, taken substantially as indicated by the arrows 5—5 in Fig. 3.

25. Fig. 6 is an enlarged elevational detail sectional view, taken substantially as indicated by the arrows 6—6 on Fig. 2, and

Figs. 7 and 8 are similar fragmentary elevational sectional views, taken substantially as indicated by the arrows S—S on Fig. 6, and illustrate certain parts in two different positions.

30. For purposes of illustration, the novel display device of our invention is herein disclosed for use in advertising bottled beverages of the well-known "soft drink" variety, such as "Coca Cola," the various brands or orangeade, lemonade, etc. However, it is to be understood that our invention is not limited to such use, and that the device can be provided in the same, or in modified form, to display and advertise other similar, or different, product containers, in substantially the same manner.

The form of our invention shown in the drawings generally comprises a housing structure 1, a base member 2, and a liquid circulating system, or apparatus, which is generally identified by the numeral 3.

The housing structure 1 is formed of suitable material, such as wood, metal, plastic material, cardboard, etc., and shaped substantially as

shown, to provide a rear wall 4, side walls 5, top wall 6, and a front wall 7 having an opening 8. The outside of the front wall 7, and the inside portion of the rear wall 4 that is seen through the opening 8, may be respectively provided with an attractive and harmonizing appearance effect, such as the curtain and tile effect shown in Fig. 1.

Mounted in the bottom end of the housing structure 1 is a reservoir 9, which is adapted to contain a liquid, such as plain or colored water. The reservoir 9 is open at its upper end, is shaped substantially as shown, and formed of a suitable material, such as metal. The reservoir 9 may be secured to the base member 2 in any suitable and practical manner and, if desired, the lower portions of one or more of the four walls of the housing structure 1 may also be suitably secured to the reservoir 9, or to the base member 2, so as to provide a rigid connection between these parts.

A support 10 is provided at the location shown, for conveniently placing or mounting thereon a product container 11, to be displayed by the device of our invention. The support 10 may be in the form of a pedestal, as illustrated, which rests on the inside bottom of the reservoir 9. If desired, the lower end of the support or pedestal 10 may be fixedly or removably attached to the reservoir bottom in any practical manner.

One type of product container 11 which may be displayed to advantage by the device of our invention, is the capped beverage bottle shown. Such bottles are of the well-known variety containing soft drinks, such as the nationally advertised "Coca Cola," or the like. Of course, some other bottle or product container 11, containing an alcoholic beverage, or other product, can be placed on the support 10, thereby to obtain for such product the same display and advertising advantages of our invention. The container or bottle 11 is provided with a standard metallic cap 12 of the type which is pressed on after the bottle is filled, and which has a convex or slightly curved upper surface.

The display device of our invention is particularly enhanced by the embodiment therein of the novel liquid circulating system 3, which is so arranged that it will direct the water flow generated by the system downwardly against the top surface of the cap 12 of the container or bottle 11, in such manner that the cap 12 will function to spread or divert the water flow in all directions and thereby cause the water to form a relatively thin transparent water-fall or curtain effect, about the outside of the bottle 11, as indicated in Figs. 1 and 3. To an observer of the display device, the water flow effect produced about the outside of the bottle 11, by the liquid circulating system 3, suggests that the liquid content of the bottle 11 is in cool and thirst-quenching condition.

The liquid circulating system 3 generally comprises the reservoir 9 which is connected by a short conduit 13 with a standard type centrifugal pump 15, a conduit line 16 that leads from the pump 15 to a valve 17, a conduit line 18 that extends from the valve 17 to a point directly above the bottle 11 and has adjustably secured to its end a liquid discharge member or nozzle 19, a standard type $\frac{1}{6}$ horsepower D. C. electric motor 20 which operates at about 1750 R. P. M. and has its shaft connected with the pump shaft by means of a standard type coupling connection indicated at 21, in Fig. 2.

The valve 17 is provided with an operating lever 22, the outer end of which has passing there-

through a series of relatively spaced alignedly arranged apertures 23 that are individually adapted to receive a connecting pin 24 secured to one end of a connecting rod 25. The other end of rod 25 has turnably mounted therein a connecting pin 26, adapted to be secured in fixed adjusted position in a slot 27 of a rotatable disc 28 secured to a shaft 29 driven by the motor 20 through a standard type speed reduction gear unit mounted in a housing section 30 adjacent the motor 20. The said standard gear reduction unit is constructed and arranged to provide a speed ratio between the motor shaft and shaft 29, in the order of 120 to 1, so that the connections between the disc 28 and the valve operating lever 22 will normally effect approximately 15 reciprocations per minute of the lever 22. The parts just described are arranged to effect reciprocation of the valve operating lever 22, to the approximate extent indicated by the dot-and-dash outlines of the said lever shown in Fig. 2, and thereby cause periodic opening and closing of a fluid flow control member 17a of the valve 17 to the extent indicated in Figs. 7 and 8. Such periodic opening and closing of the valve 17 will cause a corresponding fluctuation in the water flow which is directed against the bottle 11 by the water circulating system 3, and such fluctuating water flow effect lends an additional novel appearance or attention-attracting feature to the display device. If desired, the stroke of the valve operating lever 22 may be varied by selectively securing the pin 24 in one of the other apertures 23, or by selectively changing the position of the pin 26 in the slot 27 of the motor driven disc 28. By mounting the pin 24 in an aperture 23 closer to the outer end of lever 22 than shown in Fig. 2, the amount of the water flow through the valve 17 will be decreased, and vice versa. Similarly, by mounting the connecting pin 26, closer to the center of the disc 28, the extent of the reciprocating stroke of the valve operating lever 22 will be reduced, and vice versa.

Figs. 7 and 8 disclose the respective positions of the fluid flow control member 17a of the valve 17 when the valve operating lever 22 is in its extreme upper and lower positions, as indicated by the dot-and-dash outlines of said lever in Fig. 2. Fig. 7 shows that when lever 22 is in its extreme upper position the member 17a entirely closes the valve 17. If desired, the valve operating means may be adjusted so that when the lever 22 is in its said extreme upper position during reciprocation of the lever, the opening of member 17a will be in the position indicated by the dot-and-dash lines 17b, i. e., so that the valve is still partly open, and partial flow of the liquid through the valve takes place at such time.

To permit mounting of the display device against a room wall, or other upright support indicated by the letter W in Fig. 3, the base member 2 is provided at its rear end with a vertical extension 2a having apertures 31, through which may be extended screws 32 for separably mounting the display device against said support W. Side bracket members 33 may also be provided to connect and strengthen base member 2 and vertical extension 2a.

From Figs. 3 and 5, it will be noted that the conduit line section 18, which extends from valve 17 through the rear wall 4 of housing 1, is supported by a bracket 34 that is fixedly secured to the rear housing wall 4 by screws 35. The outer end of the bracket 34 has a ring-shaped section

34a provided with radially extending set screws 36 arranged to permit limited positional aligning adjustment of the conduit line section 18 relative to the longitudinal axis of the product container or bottle 11. The portion of the conduit line 18 which is vertically arranged on the inside of the housing 1, directly above the bottle 11, is provided with a fixed soft rubber mounting 37 for frictionally seating therein in longitudinally adjusted position, the tubular nozzle member 19 arranged to direct the liquid flow generated by the liquid circulating system 3, against the top of the bottle cap 12. The nozzle member 19 may be selectively positioned by vertical movement in the rubber mounting 37, so as to bring the lower liquid discharge end of the member 19 in properly spaced relationship with respect to the bottle cap 12, for best results in attaining a desired water flow effect about the bottle 11.

When the motor 20 is in operation, the pump 15 is driven and the liquid circulating system 3 operates to effect flow of the water from the reservoir 9, through the short conduit 13, pump 15, conduit line 16, valve 17, conduit line 18, nozzle 19, and discharge of the water from the lower end of the latter directly against the bottle cap 12, which spreads the water flow in all directions and causes downward flow of the water about the bottle 11 back into the reservoir 9. If a continuous and uniform water flow is desired, the rod 25 may be disconnected from the valve operating lever 22 and the latter selectively set so as to effect a determined steady flow of the water through the valve 17. To effect fluctuation of the water flow generated by the liquid circulating system 3, the rod 25 is connected in adjusted manner with the lever 22 and disc 28, as explained.

Mounted in the upper inside section of the housing 1 are two conventional sockets 38 for securing therein electric incandescent lamps 39, that are provided for the purpose of illuminating the interior of the housing 1. A standard type electric switch 40 is secured to one of the side walls 5 of the housing 1, as indicated in Figs. 1 and 2, to permit convenient operation of the lamps 39.

The electrical connections of our display device are indicated by the wiring diagram more or less schematically shown in Fig. 2. As there illustrated, the letters A and B represent the main line wires of an electric power system or battery, to which the display device is to be connected. The wires A and B are connected to a main control switch 41, having attached thereto electrical conductors 42 and 43. The motor 20 is connected in parallel with conductors 42 and 43, by wires 44 and 45, and the lamps 39 are likewise connected in parallel with the conductors 42 and 43 by wires 46 and 47, the lamp control switch 40 being connected with the wire 47 so as to enable interruption of the current flow to the lamps 39, as clearly shown in Fig. 2.

Of course, the form of our display device herein specifically shown and described, can be changed and modified in various ways without departing from the scope of our invention which is more particularly indicated by the hereto appended claims.

We claim:

1. A display device comprising, a support for a product container, a product container on said support having a separate liquid spreading element positioned above its upper end, and a liquid circulating system arranged to direct the liquid flow generated thereby against said element in

such manner that the liquid will be spread by the element and will flow downwardly in all directions about the outside of the container in the form of a hollow stream.

5a 2. A display device comprising, a support for a beverage bottle provided with a closure cap at its top, and a liquid circulating system arranged to direct the liquid flow generated thereby against the top of the closure cap of a beverage bottle resting on said support in such manner that the liquid will be spread by the cap and will flow downwardly in all directions about the outside of the beverage bottle.

15 3. A display device for a beverage bottle provided with a closure cap, comprising a bottle support, a liquid circulating system having a liquid discharge tube arranged to direct the liquid flow generated by the system against the top of the closure cap of a bottle resting on said support in such manner that the liquid will be spread by the cap and will flow downwardly in all directions about the outside of the beverage bottle, a liquid flow control valve connected in said system for selectively determining the extent of said directed liquid flow, motor actuated means arranged to effect cyclic operation of said valve, adjustable means for determinedly varying the cyclic operation of said valve, and mounting means for the liquid discharge tube arranged to permit selective positioning of the open end of the tube relative to the closure cap.

20 4. A display device of the character described, comprising an element provided with a deflecting surface arranged to convert a substantially solid liquid stream directed thereagainst into a transparent hollow stream forming a liquid curtain about an object positioned therebeneath for viewing through said liquid curtain, object supporting means below said element, and a liquid circulating system arranged to direct a substantially solid liquid stream against the deflecting surface of said element.

25 5. A display device of the character described, comprising an element provided with a deflecting surface arranged to convert a substantially solid liquid stream directed thereagainst into a transparent hollow stream forming a liquid curtain of symmetrical outline about an object positioned therebeneath for viewing through said liquid curtain, object supporting means below said element, and a liquid circulating system arranged to direct a substantially solid liquid stream against the deflecting surface of said element.

30 6. A display device of the character described, comprising an element provided with a curved deflecting surface arranged to convert a substantially solid liquid stream directed thereagainst into a hollow stream forming a transparent liquid curtain of symmetrical outline about an object positioned therebeneath for viewing through said liquid curtain, object supporting means below said element, and a liquid circulating system arranged to direct a substantially solid liquid stream against the top surface of said element.

35 7. A display device of the character described, comprising an element provided with a convex deflecting surface arranged to convert a substantially solid liquid stream directed thereagainst into a hollow stream forming a transparent liquid curtain of symmetrical outline about an object positioned therebeneath for viewing through said liquid curtain, object supporting means below said element, and a liquid circulating system arranged to direct a substantially solid liquid stream

solid liquid stream against the top surface of said element.

8. A display device of the character described, comprising an element provided with a deflecting surface arranged to convert a substantially solid liquid stream directed thereagainst into a hollow stream forming a liquid curtain about an object positioned therebeneath, object supporting means below said element, and a liquid circulating system arranged to direct a substantially solid liquid stream against the deflecting surface of said element.
